US00D720939S

(12) **United States Design Patent**
Toll

(10) **Patent No.:** US D720,939 S
(45) **Date of Patent:** ** Jan. 13, 2015

(54) **BICYCLE SEAT**

- (71) Applicant: **Tampa Bay Recreation, LLC**, Lutz, FL (US)
(72) Inventor: **Steven G. Toll**, Tampa, FL (US)
(73) Assignee: **Tampa Bay Recreation, LLC**, Lutz, FL (US)
(**) Term: **14 Years**
(21) Appl. No.: **29/458,879**
(22) Filed: **Jun. 24, 2013**

Related U.S. Application Data

- (63) Continuation-in-part of application No. 29/430,650, filed on Aug. 28, 2012, now Pat. No. Des. 684,781.
(51) **LOC (10) Cl.** 12-11
(52) **U.S. Cl.**
USPC **D6/354**

(57) **CLAIM**

The ornamental design for a bicycle seat, as shown and described.

DESCRIPTION

FIG. 1 is a perspective view of the ornamental design; FIG. 2 is a top plan view of the ornamental design of FIG. 1; FIG. 3 is a front view of the ornamental design of FIG. 1; FIG. 4 is a rear view of the ornamental design of FIG. 1; FIG. 5 is a left side elevation view of the ornamental design of FIG. 1; FIG. 6 is a right side elevation view of the ornamental design of FIG. 1; FIG. 7 is a bottom plan view of the ornamental design of FIG. 1; FIG. 8 is a perspective view of an alternative embodiment of the ornamental design of FIG. 1; FIG. 9 is a top plan view of the ornamental design of FIG. 8; FIG. 10 is a front view of the ornamental design of FIG. 8; FIG. 11 is a rear view of the ornamental design of FIG. 8; FIG. 12 is a left side elevation view of the ornamental design of FIG. 8; FIG. 13 is a right side elevation view of the ornamental design of FIG. 8; and, FIG. 14 is a bottom plan view of the ornamental design of FIG. 8.
The portions shown in broken lines, including the stitching, form no part of the claimed design.
